PACKAGING TRAY

Hugh R. Weiss, Montclair, N.J., assignor to The Pantasote Company, Passaic, N.J., a corporation of New Jersey

Filed Mar. 17, 1964, Ser. No. 79,036

Term of patent 14 years

(Cl. D58—13)

Fig. 1

Fig. 2

Fig. 3

I claim:

The ornamental design for a packaging tray, as shown and described.
